UNITED STATES PATENT OFFICE.

WILLIAM MEYER, OF BEAVER FALLS, PENNSYLVANIA.

CURTAIN-RACK.

SPECIFICATION forming part of Letters Patent No. 356,283, dated January 18, 1887.

Application filed September 30, 1886. Serial No. 215,019. (No model.)

To all whom it may concern:

Be it known that I, WILLIAM MEYER, a citizen of the United States, residing at Beaver Falls, in the county of Beaver and State of Pennsylvania, have invented certain new and useful Improvements in Curtain-Racks; and I do hereby declare the following to be a full, clear, and exact description of the invention, such as will enable others skilled in the art to which it appertains to make and use the same.

My invention relates to an improvement in curtain-racks; and it consists in an elastic frame that extends across over the window, and is provided with eyes for hooks to attach it, and with a needle that passes through the upper edge of the curtain to secure it, as will be fully described hereinafter.

The accompanying drawings represent my invention.

Figure 1 is a front elevation of a curtain-rack embodying my invention. Fig. 2 is a plan view of the same.

A represents a strong wire that is bent for the purpose of forming the rack, and terminates in a needle that is to pass through the upper end of the curtain to uphold it. Beginning at one side, the end of the wire is bent to form a catch, *a*, whence it descends and forms a loop, *b*. Again rising to nearly its former height, the wire is coiled to form an eye, *c*, into which enters the hook *d*, fastened in the window-frame to uphold the rack. From the eye *c* the wire extends forward at a right angle with the loop *b*, and, turning slightly, is brought forward and bent to extend in a straight line, *f*, in front over the window. This straight portion *f* of the wire reaches to the opposite side of the window-frame, passing its front at a short distance, and is there turned toward

the frame, as at *h*, and formed into an eye, *c'*, 40 for a hook, *d'*, and then into a loop, *b'*. After forming the loop *b'* the wire is straightened to form the needle *n*, extending from the loop across to the opposite side, passing under the catch *a* to a short distance beyond.

The needle *n*, removed from under the catch, is to be run through the upper edge of the curtain to uphold it. Having been attached, the loose end of the curtain is to be thrown over the straight part *f* of the wire, to descend down 45 before the window. The loops *b* *b'* serve to brace the rack when the curtains are placed.

The length of the needle *n* is such as to allow the two sides to be pulled apart without losing its hold in the catch *a*, or approached to 50 each other to assume the required width of the window.

The rack, whether made of one piece or of two, is suspended from the hooks *d* *d'*, and can be readily placed or removed, the elasticity of 55 the wire frame allowing it to be adjusted for the introduction of the hooks into the eyes.

Having thus described my invention, I claim—

In a curtain-fixture, the combination of suitable supports secured to the window-frame with a curtain-rack formed from a single piece of wire, having the horizontal portion *f*, a bend or curve, *h*, at each end, the coils *c* *c'*, to catch upon the support, the needle *n*, to 60 pass through the curtain, and the catch *a*, to engage with the needle, substantially as shown.

In testimony whereof I affix my signature in presence of two witnesses.

WILLIAM MEYER.

Witnesses:

T. F. LEHMANN,
ED. MEYER.
